BRUSH STITCHING MACHINE

John Benjamin Wooster, Medford Hillside,
Mass.

Application November 10, 1943, Serial No. 509,747

7 Claims. (Cl. 300—2)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a machine for stitching bristles to a brush and more particularly to a brush of the type used in cleaning the bore of large caliber guns.

For scrubbing the bore surface of large caliber guns a cylindrical brush is most generally utilized. This brush comprises a cylinder of suitable material provided with a series of concentric rings of evenly spaced holes in which are secured the brush bristles. Formerly these bristles were secured in each of the holes in the cylinder by hand stitching. Obviously this consumed a great deal of time because of the large number of holes in each cylinder which greatly multiplied the number of hand operations.

It is an object of this invention to provide a stitching machine for rapid stitching of bristles to a brush.

A particular object of this invention is to provide a stitching machine for stitching the bristles to a cylindrical brush of the type used for scrubbing large caliber gun bores.

Another object of this invention is to provide a stitching machine having a readily adjustable carriage for advancing the brush to a new work position.

The specific nature of the invention as well as other objects and advantages thereof will clearly appear from a description of a preferred embodiment as shown in the accompanying drawings in which:

Fig. 1 is a longitudinal sectional view of the brush stitching machine.

Fig. 2 is a cross sectional view taken along the plane 2—2 of Fig. 1.

Fig. 3 is a cross sectional view taken along the plane 3—3 of Fig. 1.

Fig. 4 is an enlarged partial longitudinal sectional view taken along the plane 4—4 of Fig. 2.

Fig. 5 is an enlarged cross sectional view taken along the plane 5—5 of Fig. 2.

Fig. 6 is an enlarged partial detail view of the cylinder support.

Fig. 7 is an enlarged cross sectional view taken along the plane 7—7 of Fig. 1.

Fig. 8 is an enlarged cross sectional view taken along the plane 8—8 of Fig. 1.

Fig. 9 is a rear elevational view of the brush stitching machine shown in Fig. 1.

Fig. 10 is a perspective view of one of the cylinder supports.

Fig. 11 is an enlarged view of the rack guide cam.

Fig. 12 is an enlarged detail partial longitudinal sectional view of the indexing stop.

Fig. 13 is an enlarged detail view shown partly in section of the needle guide.

Fig. 14 is a cross sectional view showing the needle poised over the needle hole in the thread thrower.

There is shown in assembled relation in Fig. 1 a brush stitching machine embodying this invention. This machine will stitch bristles onto a hollow brush cylinder A which is provided with uniformly spaced holes B for fastening the bristles to the cylinder. A housing 1 is provided to mount the elements of the brush stitching machine. The housing 1 is an integral hollow cast member of an inverted L-shape and has a base 2 for mounting the housing upon a suitable bench. The housing 1 has an extending arm 3 cast integrally with an upright column 4. A vertical cylindrical head 5 is integrally formed on the forward end of the arm 3 to receive a reciprocating holder to be described. A bracket 6 is suitably secured to column 4 directly under the arm 3 and perpendicular to the column 4.

A table 7 is centrally mounted on the top of bracket 6 and welded thereto. The table 7 is a comparatively narrow, thin member and is provided with beveled edges 8 as shown in Fig. 5. A longitudinal dovetailed slot 9 is centrally provided in the top surface of table 7 to receive a thread-thrower 10. The thread-thrower 10 comprises a long, narrow, rectangular slide which is provided with sloped sides to slidably engage the dovetailed slot 9.

Approximately in the center of the slide 10 there is provided an upstanding integral lug 11 which is inclined somewhat as viewed in Figs. 4 and 13. A vertical hole 12 is provided in lug 11 for a purpose to be described.

A stud 13 is threadably secured to the under-side of the slide 10 near the forward edge of the slide. A spring 14 under tension is suitably secured to stud 13 and to bracket 6 to bias stud 13 against the end of table 7. A pulley 15 is mounted on bracket 6 by a stud 16 in such a position that one edge of the pulley comes directly underneath the hole 12 in thread-thrower 10. Thus a thread brought around the pulley 15 can readily be inserted through a suitable hole in table 7 and out through the hole 12 in thread-thrower 10.

A carriage assembly 17 (Figs. 1 and 2) is slidably mounted on table 7. The carriage assembly 17 is used to mount a brush cylinder A and com-

prises two cylinder support members 18, which are separated by two bars 19, the ends of each of which are secured to opposite sides of the cylinder support members, and two adjustable guides 20. The cylinder supports 18 (Fig. 10) are provided with an arcuate upper surface 21 which corresponds roughly to the interior arc of the brush cylinder A. A flat milled surface 22 is provided on the arcuate surface of the cylinder supports 18 to mount the guide members 20. On the inside faces of the cylinder supports 18 suitable recesses 23 are provided near the lower edges of the cylinder supports to receive small rollers 24. The rollers 24 project slightly above the arcuate surface 21 of the supports 18 so that the cylinder A may ride upon these rollers for the purpose of reducing friction. The bars 19 are secured at each end to the sloped sides of the cylinder supports 18 by the screws 25 (Fig. 1). The bars 19 slidably engage the outwardly beveled edge 8 of the table 7. Thus this assembly is free to slide along table 7 and yet will be securely retained thereon. On one end of each bar 19 there is provided a slot 26 for lateral adjustment in order to accommodate cylinders A of varying lengths.

A centrally located longitudinal slot 27 is provided in the top of each cylinder support 18. On the underside of each support 18 there is provided an arcuate slot 28 to provide clearance for the slide 10. The cylinder guides 20 (Fig. 5) are of a broad inverted U-shape and are preferably stamped from thin sheet metal. A small integral bracket 29 is bent outwardly near the top of each guide and is perpendicular thereto. The bracket 29 rests on the flat milled surface 22 on each cylinder support 18. In the lower portion of each arm of the guides 20 a diagonal slot 30 as shown in Fig. 5 is provided. A small roller 31 is secured to the inside of each guide 20 by a thumb screw 32 inserted through the slot 30, which engages a suitably threaded hole in each of the rollers 31. A roller 33 centrally located in the upper part of the inverted U-shaped guide 20 is mounted thereon by a pin 34.

The brush cylinder A may thus be supported on the rollers 31 and 33 between the guides 20. The rollers 31 may be adjusted inwardly or outwardly until they bear tightly against the inner wall of the cylinder. Thus cylinders of varying diameter may be readily accommodated. If cylinders of appreciably smaller diameter are to be utilized they may be placed directly on the cylinder supports 18 where they will bear on the rollers 24.

To position the carriage assembly 17 in proper relation to the longitudinal spacing of the brush holes B on the cylinder an indexing member 35 is provided. The indexing member 35 comprises a long, narrow, rectangular member provided with a row of spaced holes 37 which correspond to the spacing of the concentric rows of holes B on the brush cylinder A. The end 38 of the indexing member 35 is bent downwardly at right angles to form a short tang 35a (Fig. 1), which projects over the end of table 7. A vernier adjusting screw 39 is mounted on the tang 35a. The threaded portion of the vernier 39 engages a suitably threaded hole in a small bracket 40, secured to the underside of table 7 as by welding. The indexing member 35 can then be laterally adjusted in either direction a small amount by turning the vernier screw. Indexing member 35 is of course of sufficient length to provide for indexing the full length of the maximum size 75

brush cylinder A. The indexing mechanism 35 is preferably placed near one edge of table 7 and a suitable slot 41 is provided in each cylinder support 18 so that movement of the carriage assembly 17 will not interfere. A spring biased indexing stop 42 (Fig. 12) suitably secured to the cylinder support 18 is provided to engage the holes 37 of indexing member 35. Indexing stop 42 comprises a flat spring 43 and a pin 44 which is secured to the spring. Spring 43 is upturned at one end to provide a suitable grasping surface for manually lifting the pin 44 out of engagement with one of the holes 37.

In the head 5 of housing 1 (Fig. 1) an axial hole 45 is provided to receive a needle holder 46. The needle holder 46 is a cylindrical member provided with two integral lugs 47 near the upper end thereof. A suitable axial hole is provided in the lower end of the holder 46 to receive a stitching needle 48. Needle 48 is secured within the holder 46 by a thumb screw 49. A screw 50 is provided in the top of head 5 to adjust the extent of upward movement of holder 46 in a manner to be described.

Two brackets 51 are suitably secured to the back of column 4 in alignment with the arm 3 of housing 1. A long lever 52 is pivotally mounted at one end by a pin 53 in the end of brackets 51. The other end of lever 52 is suitably rounded to fit between the lugs 47. A lever actuating rod 54 is pivotally secured to lever 52 approximately in the center thereof by pin 55. Rod 54 projects a short distance below the base of housing 1. A spring 56 is suitably secured to lever 52 and to the top of the arm 3 midway between the rod 54 and holder 46 to hold the holder 46 in its uppermost position. A stop 57 comprises a screw 58 and an adjusting nut 59 in a suitable bracket 60 which is secured to the arm 3 is provided to limit the downward stroke of lever 52 and holder 46. The lower end of rod 54 is pivotally secured to a crank arm 61 by a suitable bolt 62. The other end of crank 61 is mounted on a shaft 63 which is supported by suitable brackets 64. The brackets 64 are suitably secured to the underside of a bench or table on which the stitching machine may be supported. A suitably shaped pedal arm 65 is integrally secured to the shaft end of crank 61. A spring 66 is suitably secured to pedal 65 and to the underside of the bench to assist in keeping pedal 65 in a raised position as shown in Fig. 1.

A cam 67 is mounted on rod 54 and securely fastened thereto by a screw 71. The cam 67 comprises a cylindrical portion 68 and an integral lug 69 and is provided with an axial hole 70 in the cylindrical portion 68. Lug 69 is sloped upwardly as shown in Fig. 1 to engage a cam dog 72 provided on the end of slide 10. Cam dog 72 is pivotally mounted by a pin 73 in a small U-shaped bracket 74 attached to the end of slide 10. A torsion spring 75 mounted on the pin 73 is provided to bias the cam dog 72 into the path of the cam 67. The cam dog 72 is provided with a sloped surface 76 corresponding to the sloped surface on lug 69 of cam 67. Cam 67 is so positioned on rod 54 that when pedal 65 is depressed the cam 67 will strike cam dog 72 and force the slide 10 to the left and hence move the lug 11 (Figs. 4 and 13) out of the path of needle 48 as the needle comes down through one of the holes in the brush cylinder to pick up the stitching wire as will be described in more detail later.

In the back of column 4 there is provided a centrally located slot 77. A solid rectangular slide 78 is placed within the slot 77 and is slid-

ably retained therein by guides 18. The guides 18 are long flat strips secured as by screws to the column 4 along the edges of slot 17 and slightly overlap the slide 18. Two brackets 80 are suitably secured to the back of column 4 about midway from the base 2 to the top of arm 3 to support a spool 81. Spool 81 is mounted between the brackets 80 by a bolt 82. A ratchet 83 is secured to one side of spool 81 as by welding. A projecting arm 84 is securely bolted to the slide 18 about in the center thereof. Pivotally secured to the bottom of arm 84 is a rack 85. Rack 85 is placed adjacent a cam track 86 formed by two cam plates 89 and 90 and a guide 91 shaped as shown in Figs. 1 and 11. The cam plates 89 and 90 and guide 91 are welded to the inside of one of the brackets 80. Arm 84 is offset sufficiently to maintain the rack 85 in an upright position against the face of cam 86. The rack 85 is provided with a plurality of teeth 87 to engage the ratchet 83. A stud 88 suitably secured near the upper edge of rack 85 engages the cam track 86. Near the lower corner of cam plate 89 a one way dog 92 (Fig. 11) which is spring biased by a suitable torsion spring (not shown) is provided to prevent the rack 85 from back-tracking around the cam when the rack 85 is permitted to return to its normal position.

A rack depressor 93 is pivotally secured to the side of bracket 80 by a stud 94 and is spring biased by a leaf spring 95 to bear against the sloped upper surface of rack 85 as shown in Fig. 1. Depressor 93 forces the rack 85 to follow the cam track 86 when the rack 85 reaches its uppermost position. The complete function of the cam track 86 will be presently described in more detail.

A slide rod 96 (Fig. 1) is fastened as by threads to the bottom of slide 18 and is locked thereto by a lock nut 97. Rod 96 projects slightly below the base 2 where it is pivotally secured to a crank arm 98 by a pin 99. The crank 98 is mounted on shaft 63 adjacent to crank 61 and a pedal arm 100 similar to pedal 65 is likewise similarly secured to the shaft end of crank 98. One end of a tension spring 101 is secured to a stud 102 which projects from the rear of slide 18 while the other end is secured to the upper part of column 4. Another tension spring 103 is secured to pedal 100 and to the underside of the base 2.

Secured to the lower end of slide 18 is a bracket 104. The bracket 104 projects downwardly and is preferably welded to the slide 18. A pulley 105 having a V-shaped groove about its periphery is mounted on the bracket 104 by a fixed stud 106. A stop 107 which comprises a screw 108 and a check nut 109 is threadably inserted in a suitable bracket 110 secured to column 4 to limit the upward travel of slide 18. A suitable friction brake 111 may be provided to engage the spool 81 if desired to retard the rotation of spool 81 when the rack 85 is out of engagement with ratchet 83. A thread guide 112 is secured to the lower end of bracket 84 as by welding and projects vertically downwardly. The lower end of the guide 112 is slotted to receive the thread from the spool 81.

The cylinder A in which the bristles are to be inserted and secured is placed over the carriage 17 between the supports 18, and the guide members 20 are brought up against each end of the cylinder. The rollers 31 are adjusted to bear against the inside of the cylinder. For the purpose of securely fastening the bristles to the cylinder a fine wire is preferably utilized. Such wire is coiled on the spool 81. The free end of the wire

on spool 81 is led through the slot in guide 112, underneath the pulley 105 around the pulley 15 and up through hole 12 in lug 11. A comparatively long free end is left hanging loose. By 5 means of the vernier screw 39 the cylinder is adjusted longitudinally so that one of the holes B in the first row of holes in the cylinder A will be in alignment with needle 48. Pedal 65 is then 10 manually depressed which forces crank 61 downwardly which in turn results in needle 48 being thrust downwardly through the hole in brush cylinder A to engage the wire coming from spool 81. As pedal 65 is depressed cam 67 of rod 54 engages cam dog 72 on thread-thrower 10 which 15 forces the thread-thrower to the left a short distance as viewed in Fig. 1 just prior to the needle 48 reaching the lowest point of its stroke. The downward travel of holder 46 is limited by the stop 57 which arrests the movement of lever 52. 20 After cam 67 has actuated the thread-thrower 10 to the left, the slide immediately returns to its normal position after cam 67 has passed by cam dog 72, thus bringing the wire from spool 81 directly across the path of needle 48. Thus the hook 48a of needle 48 will pick up the wire when 25 released by release of pedal 65. When pedal 65 is released, springs 56 and 66 return the pedal 65 and lever 52 to their normal or raised position, stop 50 limiting the upward travel of lever 52. 30 During the upstroke the top surface of cam 67 strikes the underside of cam dog 72 and pivots it in a counterclockwise direction as viewed in Fig. 1 permitting the rod 54 unimpeded upward travel. Torsion spring 75 returns cam dog 72 to its normal 35 position where it will again be in position to be engaged by the cam 67. The thread, picked up by needle 48, is brought up through a hole B in the brush cylinder A to form a loop. The operator then disengages the loop from the needle and 40 inserts a small tuft of bristles through the loop. To tighten the loop and draw the bristles into the hole in the brush cylinder the pedal 100 is then depressed. 45 Depressing pedal 100 causes the crank 98 to rotate downwardly which in turn carries with it connecting rod 96. Rod 96 being secured to slide 18 in turn draws that downwardly. This movement forces the rack 85 downwardly. Stud 88 and cam track 86 determine the path of travel of 50 the rack 85. Teeth 87 on rack 85 then engage corresponding teeth on ratchet 83. Spring biased rack depressor 93 bears against the top of rack 85 and assists the rack 85 to follow the cam track 86 during the initial downward movement of rack 85. This downward movement of rack 85 revolves 55 the ratchet slightly in a counterclockwise direction as viewed in Fig. 1 and in turn revolves spool 81. Such movement rewinds the wire onto spool 81 and consequently tightens the loop previously 60 formed and draws the wire and bristles into the hole in the brush cylinder. Visual inspection on the part of the operator determines the proper depth to which the bristles should be drawn into hole B. When pedal 100 is released springs 103 and 101 return slide 18 and pedal 100 to their 65 normal or upper position. One way pawl 92 prevents stud 88 from retracing its same path in cam track 86 and forces it around cam track 86 to its starting position and hence pivots rack 85 out of engagement with the teeth of ratchet 83. The upper travel of slide 18 is limited by stop 108. Friction brake 111 is provided to engage one edge of spool 81 to prevent the spool from 70 revolving too freely as pedal 65 is depressed so 75

that a great deal of slack wire will not be unwound.

I claim:

1. A machine for assisting the stitching of tufts of bristles onto a hollow cylinder provided with a plurality of substantially uniformly-spaced holes arranged in ring-like fashion around its periphery comprising in combination, a needle, means for reciprocating said needle, a thread thrower arranged to receive and guide a stitching thread and mounted for transverse movement with respect to the path of said needle, a support member adapted to rotatably support the cylinder with its periphery at approximately right angles to said needle, said support member being mounted for movement along the length of the cylinder, indexing means for successively positioning said support member with respect to said needle whereby successive rings of holes in said cylinder will be aligned with respect to the path of said needle, whereby each hole in a ring of holes may be traversed by said needle by rotation of the cylinder so that the latter may withdraw a loop of the stitching thread thru a hole of said cylinder.

2. A machine for assisting the stitching of bristles onto a hollow cylinder having uniformly spaced holes therein arranged in ring-like fashion around its periphery comprising, a needle, means for reciprocating said needle, a support arranged to rotatably support the cylinder in the path of said needle, said support being mounted for movement perpendicular to the path of said needle, indexing means for successively positioning said support with respect to said needle whereby successive rings of holes in said cylinder will be aligned with respect to the path of said needle so that each hole in any one ring may be traversed by said needle by rotation of the cylinder on the said support, a thread thrower arranged to receive and guide a stitching thread and mounted for transverse movement with respect to the path of said needle, and means for moving said thread thrower synchronously with said needle, all adapted and arranged whereby said thread thrower moves across the path of said needle while the latter is projecting thru a hole of the cylinder and the needle engages the stitching thread and withdraws a loop thereof thru said hole.

3. A machine for assisting the stitching of bristles onto a hollow cylinder having uniformly spaced holes therein arranged in ring-like fashion around its periphery comprising, a needle, means for reciprocating said needle, a support arranged to rotatably support the cylinder in the path of said needle, said support being mounted for movement perpendicular to the path of said needle, indexing means for successively positioning said support with respect to the path of said needle so that each hole in any one ring may be traversed by said needle by rotation of the cylinder on the said support, a rotatably mounted reel arranged to receive a stitching thread coiled thereon, a thread thrower mounted for horizontal movement in a path adjacent the path of said needle, cam means arranged to move said thread thrower across the line of movement of said needle when the latter is moved whereby said needle engages the stitching thread and withdraws a loop of the stitching thread thru a hole of the cylinder, and means for rotating said reel in a direction to tighten the loop formed.

4. A machine for assisting the stitching of bristles onto a hollow cylindrical frame having

uniformly spaced holes therein comprising a hooked needle, means for reciprocating said needle, a support arranged to rotatably support the cylinder in the path of said needle, said support being mounted for movement perpendicular to the path of said needle, indexing means for successively positioning said support with respect to said needle whereby successive rings of holes in said frame will be aligned with respect to the path of said needle so that each hole in such ring may be traversed by said needle by rotation of the frame on the said support, a thread thrower arranged to guide a stitching thread, said thread thrower being mounted for transverse movement with respect to the path of said hooked needle, and means for moving said thread thrower across the line of movement of said hooked needle when said needle projects thru a perforation of said frame whereby said hooked needle engages the stitching thread and withdraws a loop of the stitching thread thru the perforation of the frame.

5. A machine for assisting the stitching of bristles onto a hollow cylindrical frame having uniformly spaced holes therein comprising a hooked needle, means for reciprocating said needle, a support arranged to rotatably support the cylinder in the path of said needle, said support being mounted for movement perpendicular to the path of said needle, indexing means for successively positioning said support with respect to said needle whereby successive rings of holes in said frame will be aligned with respect to the path of said needle so that each hole in such ring may be traversed by said needle by rotation of the frame on the said support, a rotatably mounted reel arranged to receive a stitching thread coiled therein, a thread thrower arranged to receive and guide the stitching thread from said reel, said thread thrower mounted for transverse movement with respect to the path of said hooked needle, means for moving said thread thrower across the line of movement of said hooked needle when said needle projects thru a perforation of said frame whereby said hooked needle engages the stitching thread and withdraws a loop of the stitching thread thru the perforation of the frame, and means for rotating said reel in a direction to tighten the formed loop.

6. A machine for assisting the stitching of bristles onto a hollow cylindrical frame having uniformly spaced holes therein comprising a hooked needle, means for reciprocating said needle, a support arranged to rotatably support the cylinder in the path of said needle, said support being mounted for movement perpendicular to the path of said needle, indexing means for successively positioning said support with respect to said needle whereby successive ring of holes in said frame will be aligned with respect to the path of said needle so that each hole in such ring may be traversed by said needle by rotation of the frame on the said support, a rotatably mounted reel arranged to receive a stitching thread coiled thereon, a thread thrower arranged to receive and guide the stitching thread from said reel, said thread thrower mounted for transverse movement with respect to the path of said hooked needle, means for moving said thread thrower across the line of movement of said hooked needle when said needle projects thru a perforation of said frame whereby said hooked needle engages the stitching thread and withdraws a loop of the stitching thread thru

the perforation of the frame, means for rotating said reel in a direction to tighten the forming loop, said last mentioned means comprising a ratchet wheel connected to said reel, a reciprocating rack, and cam means determining the position of said rack, said cam means moving said rack into engagement with said ratchet wheel during one direction of movement of said rack.

7. A machine for assisting the stitching of bristles onto a hollow cylindrical frame having uniformly spaced holes therein comprising a hooked needle mounted for vertical movement, a mechanical linkage for moving said needle downwardly and return, a support arranged to rotatably support the cylinder in the path of said needle, said support being mounted for movement perpendicular to the path of said needle, indexing means for successively positioning said support with respect to said needle whereby successive rings of holes in said frame will be aligned with respect to the path of said needle so that

each hole in such ring may be traversed by said needle by rotation of the frame on the said support, a rotatably mounted reel arranged to receive a stitching thread coiled thereon, a thread thrower mounted for horizontal movement in a path adjacent the path of said needle, cam means connecting with said linkage to move said thread thrower across the line of movement of said hooked needle when said needle is moved downwardly by said linkage whereby said hooked needle engages the stitching thread and withdraws a loop of the stitching thread thru a perforation of the frame, means for rotating said reel in a direction to tighten the loop formed, said last mentioned means comprising a ratchet wheel connected to said reel, a reciprocating rack, and cam means determining the position of said rack, said cam means moving said rack into engagement with said ratchet wheel during one direction of movement of said rack.

JOHN BENJAMIN WOOSTER.
